UNITED STATES PATENT OFFICE.

SAMUEL K. WHITE, OF CHICAGO, ILLINOIS, ASSIGNOR, BY MESNE ASSIGNMENTS, TO LAMPERT & CO., OF SAME PLACE.

PLANING-MACHINE.

SPECIFICATION forming part of Letters Patent No. 370,912, dated October 4, 1887.

Application filed May 22, 1886. Serial No. 202,988. (No model.)

To all whom it may concern:

Be it known that I, SAMUEL K. WHITE, of Chicago, in the county of Cook and State of Illinois, have invented certain new and useful 5 Improvements in Lead-Planing Machines; and I do hereby declare that the following is a full, clear, and exact description thereof, reference being had to the accompanying drawings, and to the letters of reference marked 10 thereon, which form a part of this specification.

The object of this invention is to provide an improved machine for planing or finishing strips of soft metal, such as printers' leads; and it consists in the matters hereinafter 15 described, and pointed out in the appended claims.

In the accompanying drawings, illustrating my invention, Figure 1 is a side elevation, partly in central vertical section, of a machine 20 embodying my invention. Fig. 2 is a vertical cross-section of the same, taken upon line $x-x$ of Fig. 1. Fig. 3 is a sectional plan view taken upon line $y-y$ of Fig. 2. Fig. 4 is a similar sectional view taken upon line $x-x$ of Fig. 2. Fig. 5 is an enlarged detail plan view of parts 25 shown in Fig. 1. Fig. 6 illustrates a form of device for actuating the reciprocating bed or table of the machine, as hereinafter described.

In the said drawings, A indicates the main 30 frame of the machine, said frame being sustained upon legs or standards a in the usual manner; and B, a longitudinally-reciprocating table or carriage having bearings at its side edges in guides A' A' upon the frame A, and 35 adapted to sustain or support the strips to be operated upon.

C indicates the knife or cutter, which is made with a horizontal cutting-edge upon its lower end adapted to operate upon the top surface of a lead or strip of metal upon the table B; and D is a vertically-movable block for supporting the cutter, said block being attached to a rigid frame, A², secured to the sides of the frame A and extending over the carriage 45 B. The said cutter is immediately sustained upon a swinging block, C', pivoted to rotate upon a transverse horizontal axis to allow the cutter to be swung upwardly and forwardly away from the work in the return movement 50 of the latter after each cut, in a familiar man-

ner, and the said block C' is mounted upon a plate, D', adjustably connected with the block D in such manner as to afford an angular adjustment of the edge of the cutter to the work, as will hereinafter more fully appear.

The machine illustrated is provided, for the purpose of holding the metal strips to be planed upon the table B, with a gripping device, which is actuated automatically for clamping and releasing the strips by the action of the devices by which the table is reciprocated. For this purpose motion is transmitted to the table through the medium of a bar, E, which is located beneath and supported by the table B, and is adapted to slide 60 longitudinally to a limited extent upon the latter, so that there will be a certain amount of lost motion between the bar and the table at each time the direction of motion of the latter is reversed.

The gripping device comprises, essentially, a pivoted jaw or gripper, F, which is constructed to act against an opposing surface upon the table, and is actuated by a lug or projection upon the bar E, which operates to 75 move said jaw at each time the bar is moved relatively to the table at the forward and rearward limit of the movement of the table, as will be hereinafter more fully explained.

The driving devices herein shown as acting 80 upon the bar E for the purpose of giving a reciprocatory movement to the carriage B consist of a rack-bar, G, secured upon the said bar E, and which is made double and adapted for engagement upon both of its sides with a 85 cog-wheel, H, which is mounted in a frame, I, adapted to oscillate upon a horizontal axis parallel with and vertically beneath the rack-bar, in such manner as to enable the said cog-wheel to engage both sides of the rack-bar 90 and pass around the end of the latter at both limits of its movement, the wheel being held in engagement with the rack by stops I' upon the sides of the frame A, and caused to move around the rack at its ends by means of curved 95 guide-pieces or yokes J, constructed to engage an anti-friction roller, h, mounted upon the end of the shaft H', to which said wheel H is secured. The said yokes are arranged, as more clearly shown in Fig. 3, to hold a gap or 100

recess, h' , in the wheel in engagement with rollers g at each end of the rack, and to cause the central axis of the shaft to describe a semi-circular curve about the said rollers g , so as to bring the wheel again in position for engagement with the rack after passing around the end of the latter. The stops I' operate to limit the lateral oscillatory movement of the frame I , so as to hold the said wheel H in engagement with either one side or the other of the rack, as clearly shown in Figs. 2 and 3, the frame I being shown in dotted lines in said Fig. 2 in its position when engaging one side of the rack and in contact with the said stop I' . The stops I' are, as shown, formed by screw-bolts inserted through the sides of the frame, and provided with jam-nuts upon their ends outside of the frame, so that they may be adjusted in position as required for the perfect operation of the parts.

The frame I is pivotally supported concentrically with the main driving-shaft K of the machine, said frame, as herein shown, being for convenience mounted upon the shaft itself, which latter is sustained in a bearing, A^3 , adjacent to the said frame and in a bearing, A^4 , attached to an overhanging bracket, A^5 , bolted to the end of the frame A . The shaft H' of the pinion H is preferably actuated by means of a pinion, K' , upon the driving-shaft K , which pinion intermeshes with a gear-wheel, H^2 , fixed to the said shaft H' at its end adjacent to the shaft K , the frame I being bifurcated at its lower end and provided with two separated bearings, I^2 I^3 , which engage the shaft K at points exterior to the gear-wheels K' and H^2 .

It is entirely obvious from the construction above described that when the shaft K is given a rotative motion the pinion H will be rotated through the medium of the gears K' and H^2 , so as to drive the rack G longitudinally in a direction depending upon the side of the rack-bar with which the said pinion H is engaged, and that when the said rack has been carried endwise until the gap h' in the pinion engages the end roller thereof the anti-friction roller h upon the pinion-shaft, engaging the guide J , will carry the pinion, together with the frame I , laterally until the pinion engages the opposite side of the rack, when the latter will be moved in a reversed direction until its opposite end is again reached, when the direction of its motion will be again reversed, as before.

The jaw F , forming part of the gripping device above described, is connected by means of a pivot-pin, f , with the carriage B , and is rigidly connected with the lever-arm F' , extending rearwardly from the jaw, and adapted to engage the stop or projection e , which is attached to and moved with the sliding bar E , the parts being so arranged that when the said bar is thrust in a direction to carry the carriage toward the cutter the said stop e will lift the lever F' , and thereby cause the clamp-jaw F to press against the end of the lead located between it and the carriage-bed, and when the

said bar E is moved in the opposite direction, or in such manner as to return said bed into position for the placing of a new strip, the said stop e will allow the lever-arm F' to fall, and thereby permit the release of the lead which has been operated upon.

The relative movement between the carriage B and the bar E is limited by suitable stops upon said parts, so that the amount of lost motion between them is only sufficient to properly actuate the jaw by the movement of the lug or projection e in the manner above stated. As a preferred construction in the parts above referred to, the bar E is held at its edges in grooves b , formed in the lower surface, by suitable longitudinal flanges, b' , upon the lower surface of the carriage B , and the lug e is secured to or formed on a plate, E' , secured to the upper surface of the said bar E , within a recess, B' , extending vertically through the carriage B , as more clearly shown in Figs. 1 and 5. The said recess B' is made somewhat longer than the plate E' , so as to allow the desired lost motion between the bar E and carriage B , the ends of the said plate E' and the end walls of the recess B' in this case forming the stops above referred to for limiting the relative movement of the said bar and carriage. The end walls of the said recess B' are desirably provided with cushions b^2 , of leather or other suitable material, to prevent shock or jar when the parts come in contact with each other, as will occur at the beginning of the return movement of the table, and also at the beginning of the movement of the table in a direction for cutting in case there is no metal strip placed beneath the jaws F . A spring, f' , is desirably arranged to hold the lever-arm F' downwardly, and thereby insure the opening of the grip-jaw at proper times, said spring, as herein shown, being of leaf form and attached at one end to the top surface of the carriage B , and resting at its free end upon the said lever-arm. The recess B' is shown in the drawings as covered by a thin plate, b^3 , having a central opening for the passage of the end of the lever-arm F' , said covering-plate being for the purpose of preventing the access of chips or other foreign material to the said recess. The pivot f of the grip-jaw may be held by any suitably-arranged bearings upon the carriage, said pivot, as herein illustrated, being held at its ends in lugs f^2 , formed upon a circular plate, F^2 , which is held in a recess in the top of the carriage by means of screws f^3 . The plate F^2 is preferably made with a roughened gripping-surface, F^3 , in its part opposed to the jaw F , which latter is also preferably roughened upon its working-face to more effectively hold the end of the metal strip or lead which is operated upon by the machine.

The employment of a rack and pinion for actuating the table or carriage of a machine for planing printers' leads or other soft-metal strips, although desirable as a means of readily giving a rapid reciprocating motion to the said carriage, has been found objectionable, owing

to the vibratory or chattering movement thereby given to the said carriage, such vibratory movement tending to produce an uneven or wavy surface in the planed lead or strip, and 5 the same result often follows from the use of cog-gearing or other similar device at any point in the driving-connections by which the machine is actuated. I have found, however, that by placing a spring or cushion of rubber or other material in the connecting parts 10 between the carriage or other part sustaining or holding the work and the devices by which the latter is actuated any injurious shaking or vibratory movement is entirely avoided, and 15 that the knife will make a perfectly clean and smooth cut.

In the machine shown in the drawings, in which the longitudinal movement of the rack is imparted to the bed through the medium of 20 the projection *e* and the lever *F'* of the gripper *F*, a cushion, *E'*, for the purpose above cited, is placed between the plate *E'*, sustaining the projection *e*, and the bar *E*, thereby giving an elastic instead of a rigid connection between 25 the rack-bar *G* and the table *B*, it being entirely obvious that in the machine shown the longitudinal strain by which the table is moved does not come directly upon the table itself, but is transmitted to the latter through the 30 medium of the projection *e* and the clamp-jaw *F*, which latter operates to press the gripping end of the strip against the carriage. It will thus be seen that the carriage itself, in this case, in one sense forms the lower jaw of a grip 35 device, which is moved or drawn directly from the bar *E*, or, in other words, that the said carriage forms a long or extended lower jaw to the grip, affording suitable support for the strip to be planed.

40 The plate *E'* is, as herein shown, held upon the bar *E* by means of screws or bolts *e'*, inserted through the plate *E'* into the bar, said screws or bolts being arranged to hold the plate *E'* from endwise displacement, but in 45 such manner as not to interfere with the elasticity of the connection afforded between said plate and bar by the said cushion *E'*.

In the particular construction of the carriage or table *B* illustrated, the said table is 50 provided with a central raised rib, *b'*, made flat upon its top surface to receive the metal strip or lead to be planed, said rib terminating at its end adjacent to the gripping device upon a level with the gripping-surface *F'*. 55 This construction in the table is, however, not essential to the operation of the machine, and is employed merely to facilitate the removal of chips from the surface upon which the strips are placed.

60 The pivoted or swinging block *C'*, to which the knife is immediately attached, is, as herein shown, adapted to rotate at its upper end upon a transverse horizontal pivot, *c*, which is held at its ends in lugs or projections *c'* upon the 65 plate *D'*, and the lower end of the block *C'* and the cutter, *C*, carried thereby are preferably adapted to swing freely forward away from the

supporting-block *D'* in the return movement of the carriage after each strip has been planed, the cutter being arranged to fall backwardly into position for operation as soon as the carriage begins its movement toward the knife in a manner common in planing-machines. In order, however, to prevent the knife from rubbing or scraping upon the finished surface of the strip in the return or backward movement of the table, the pivoted block or support *C'* is preferably provided with an arm, *C''*, extending laterally and downwardly therefrom and having upon its lower free end 70 a piece or block, *c''*, of flexible material—such as rawhide—adapted to rest upon the top surface of the bed *B* at one side of the work, the said arm operating to throw the knife forwardly and upwardly in the return or backward movement of the carriage, and to thereby sustain its cutting-edge free from the work during the backward passage of the latter beneath said knife. As herein shown, the said arm *C''* is adjustably connected to the block *C'* by 75 means of set-screws *c'''* passing through a slot, *c''*, in the arm, whereby the latter is made capable of adjustment vertically, as may be found desirable in adjusting the position of the cutter, or under other circumstances. The prompt 80 return of the cutter to its working position at the end of the return movement of the carriage is insured by means of a spring, *D''*, secured to a part of the plate *D'*, and resting at its free ends against the lower part of the block 85 *C'*, the free end of the said spring *D''* being, as shown, arranged to engage a pin, *c''''*, secured in a block, *C'''*, which latter is secured upon the forward face of the block *C'* and provided with a passage, through which is inserted the 90 shank of the cutter *C*, and in which it is held by a set-screw, *c'''*, as clearly shown in Figs. 1 and 2.

For the purpose of adjusting the cutting-edge of the cutter so as to bring it accurately 95 horizontal or parallel with the plane of the table *B*, the plate *D'* is pivoted at its lower end upon the block *D* by means of a pivot-screw, *d*, in such manner that its upper end may swing laterally in a vertical plane, said 100 plate being held from lateral movement at its upper end by two set-screws, *d' d'*, which are inserted through lugs *d''* upon the front face of the block *D*, with their inner ends bearing upon opposite sides of the said plate, so that 105 by turning both screws the plate may be moved and held accurately to and in a desired angular position. The plate *D'* is held in contact with the block *D* by means of a headed bolt, *e''*, engaging a slot, *d'''* in the plate.

The block *D*, which, as before stated, is vertically movable in the support *A''*, is desirably made of dovetailed shape in cross-section and held at its edges between guide-flanges *a''* upon the frame *A''*, bearing-plates *a'''* being herein 130 shown as placed between the said flanges *a''* and the side margin of the block, which plates are held in contact with the block by means of set-screws *a'''* passing through the flanges *a''*,

whereby the plates may be moved inwardly to compensate for wear. The said block D is connected with the frame A² by means of a vertical adjusting-screw, D³, whereby the vertical position of the block may be accurately adjusted, said screw D³ being mounted in a bearing, a², upon the frame A², and engaged with a threaded aperture in the upper part of the block D. The said block D is preferably 15 to split vertically in its upper part, as clearly shown in Figs. 1 and 4, and set-screws d⁵ are inserted through the split parts to enable the latter to be clamped or held firmly in contact with the set-screw, the object of this construction being to enable the screw to be held firmly 20 in engagement with the block, and to thereby prevent lost motion between the parts.

For the purpose of rigidly holding the upper end of the set-screw in its bearing a², and 25 for clamping said screw so as to prevent possibility of the adjustment of the block D being disturbed by the accidental turning of the screw, a hub, D⁴, provided with turning levers or handles, as shown, is placed upon the screw-shaft above the bearing a², and connected with the shaft by a spline and groove, so as to allow the shaft to move longitudinally through, but not to rotate in, the hub, and upon the screw-threaded end of the screw-shaft above 30 the hub is placed a jam-nut, D⁵, similarly provided with levers or handles, so that after the screw has been turned by the hub D⁴, so as to bring the cutter in a desired position vertically, the jam-nut may be screwed down 35 upon the hub D⁴ with the effect of clamping the several parts firmly and immovably in position.

An automatic clutch mechanism is herein 40 shown whereby a driving-pulley upon the shaft K may be disconnected therefrom at the termination of each forward and return movement of the carriage, said device being constructed as follows: L is the driving-pulley, mounted to rotate freely upon the shaft K, exterior to the bearing A⁴, said pulley being provided upon its hub with one of the members, l, 45 of a friction-clutch, the other member, l', of said clutch being mounted upon a sleeve, L', constructed to slide longitudinally but not to rotate upon the shaft K, and provided with an annular groove, l², which is engaged with the forked end m of a sliding rod, M, having bearings at m' and m² upon the frame. The 50 said rod M is connected by means of a pitman, M', with the depending arm n of a bell-crank lever, N, pivoted upon the frame A near one side of the latter. The opposite end, n', of said lever N is connected with a rod, O, extending to a suitable treadle, whereby the rod may be 55 actuated, and is also adapted to engage a spring-detent, P, adapted to hold said arm n' of the lever downwardly, and thereby retain the clutch in engagement against the action of a spring, N', arranged between the arm n' of the 60 said lever N and an opposing surface upon the frame A, said spring operating to hold the lever N and the sliding bar M in position for the

disengagement of the clutch. A spring-detent, P, pivotally supported upon the machine-frame, is provided with a hooked upper end, 70 p, adapted to engage and hold the arm n' downwardly against the action of the spring N', the said detent P being engaged by a spring, P', tending to hold said detent normally in position to engage the arm N, the projection p upon the said detent being so arranged that when the free end of the arm n' is raised the said projection will be prevented by contact with the end of the said arm from engagement with the latter. Upon the rear end of the carriage B is located a depending stop or projection, B², (shown in dotted lines in Fig. 1 and in full lines in Fig. 2,) the said stop B² being arranged to encounter the detent P and throw it forward out of engagement with the lever N 80 at the moment the carriage reaches the forward or outward limit of its movement.

From the construction above described it is obvious that when the carriage B is in position for the insertion of a metal strip or lead 85 the stop B² will be in engagement with the detent P, so as to hold the latter clear from the lever N, as shown in Fig. 1, the said lever at such time being thrown upwardly by the spring N', so as to retain the clutch disengaged. If, now, it is desired to start the machine, the treadle is actuated, so as to depress the rod O, and to thereby throw the clutch into 90 engagement. As soon as the shaft begins to revolve and the carriage to advance, the detent P will be released from the stop B² and allowed to spring forward over the end of the arm n' of the lever N, so that when the said lever is released by the operator the detent 95 will retain the said arm and other parts of the clutch mechanism in position for engagement, and they will remain in this position until the carriage has made one complete reciprocation, when upon again reaching the forward limit 100 of its movement the stop B² will encounter the detent P, and thereby release the lever N and cause the stoppage of the machine.

The machine herein shown is provided upon the driving-shaft K, adjacent to the bearing A⁴, with a collar, k, and between said collar 105 and the end of the bearing is placed a washer, k', of rawhide or other similar material. Upon the end of the said shaft K adjacent to the bearing I³ of the frame I, which engages said shaft, is also placed a similar collar, k², having 110 between it and the bearing I³ another washer, k³, the end of the shaft which extends beyond said collar k² being screw-threaded and provided with a nut, k⁴, whereby the collar k² and the washer k³ may be forced against the end of 115 the bearing I³. The action of said nut also tends to move the shaft longitudinally in the bearings A³ A⁴, and to thereby cause the washer k³ to press upon the bearings A⁴. By this construction a means is provided for giving frictional resistance to the rotation of the shaft K, and the object of such construction is to counteract the momentum of the shaft and other 120 moving parts, and to thereby cause the prompt 125

stoppage of the said shaft and of the table at the moment the clutch device is thrown out of gear by the action of the stop B^2 against the 5
detent P , it being entirely obvious that in case the impetus of the revolving parts were sufficient to carry the bar E backward to any considerable extent the gripping-jaw would be closed before the end of the strip or lead could be inserted beneath it.

10 It is found in practice that in operating upon opposite sides of a strip of soft metal, if the latter is placed in the same position upon the bed or table B at each operation, and the cutter is thereby caused to bite into the 15
face of the strip at the same place several times in succession, the strip is liable to be pulled apart or break at such place. To avoid liability of this result a movable stop, f^4 , is preferably provided beneath the jaw F , 20
against which stop the end of the strip is thrust in placing it upon the table, said stop being shifted in position after the severed strips in a batch of strips have been planed upon one side, so that in planing them upon 25
their opposite sides the cutter will strike into the opposite surfaces at points slightly in front of or behind the places at which the first cuts begin. In the particular construction illustrated the said stop f^4 is formed by or upon a 30
lever, F^4 , which is pivoted upon the top of the table B , and is provided with a curved slot, f^5 , and clamp-screw f^6 , whereby the stop may be moved to and held at a desired distance from the end of the jaw F .

35 The table B is herein shown as constructed to rest by gravity in the guides A' A' , except at the part of said guides adjacent to the cutter-supporting frame A^3 , at which point the frame A is provided with upwardly and inwardly extending flanges a^7 , sustaining gibbs a^7 in position to bear upon the beveled edges of the table, and thereby hold the latter closely in place upon the guides during the action of the cutter on the work, set-screws a^8 being desirably provided for setting the gibbs a^7 closely up against the bearing-surfaces of the table. It is to be understood, however, that these and other similar details of construction in the machine may be varied in carrying out my invention, as may be found convenient or desirable.

One of the principal features of improvement in my invention is that involved in the employment of an elastic connection between the driving devices by which the table or carriage is actuated and the table or carriage itself. In case the machine to which this cushion is applied is one in which a grip-jaw for clamping the lead is actuated by a relative 55
movement of the carriage itself and a reciprocating part to which the power for doing it is applied, as is the case in the machine herein shown, a cushion to give the yielding or elastic connection between the said reciprocating 60
part and the carriage will usually be located in the connections between the said reciprocating part and that part of the gripping de-

vice which is actuated by it. In other cases, however, the cushion may be interposed at other points between a rack and pinion, cog- 70
gear, or other connecting device liable to give a vibratory motion in the reciprocating table or carriage, and a carriage or table upon which the work is independently secured. A construction of this kind in which a sliding rack- 75
bar and pinion is employed is illustrated, for instance, in Fig. 6, in which figure blocks of rubber E^3 are shown as inserted between a sliding rack-bar, G' , which is provided with projections or lugs g' , between which lugs and the corresponding lugs, b^5 , upon an independently-sliding carriage, B^3 , the said rubber blocks E^3 are located.

Inasmuch as important advantages are obtained by the novel feature of construction described, comprising an elastic connection between a driving device and the table or carriage actuated thereby, said cushion is herein broadly claimed without restricting the particular manner of its application. 85

I claim as my invention—

1. A planing-machine comprising a reciprocating bed or table and means for actuating the table, embracing an elastic connection between said table and the driving devices, substantially as described. 95

2. The combination, with a reciprocating bed or table, of means for actuating the table, comprising a rack-bar having a limited movement longitudinally with relation to the table, and an elastic block or cushion interposed between the rack-bar and table, substantially as described. 100

3. The combination, with a cutter and a reciprocating bed or table, of a part or bar constructed to reciprocate with the table and movable to a limited extent with relation to the latter, to which part or bar the power for actuating the table is applied, a gripping device upon the table, and a lug or projection upon the said movable part or bar constructed to engage and actuate the gripping device, substantially as described. 105

4. The combination, with a cutter and a reciprocating table, of a gripping-jaw pivoted upon the table and provided with a lever-arm, F' , a bar, E , having a limited movement longitudinally with relation to the table and provided with a lug or projection, e , engaging said lever F' , and means applied to the bar E for actuating the table, substantially as described. 115

5. The combination, with a cutter and a reciprocating table, of a gripping-jaw pivoted upon the table and provided with a lever-arm, F' , a sliding bar, E , provided with a lug or projection, e , engaging said lever-arm, stops limiting the relative movement of the bar and the table, and means applied to the said bar E for actuating the table, substantially as described. 125

6. The combination, with a cutter and a reciprocating table, of a gripping-jaw mounted upon the table and constructed to act against

an opposing surface upon the latter, a sliding bar having a limited movement longitudinally with relation to the table and provided with a part or projection engaging and actuating 5 the jaw, a cushion interposed between said bar and projection, and means applied to the said bar for actuating the table, substantially as described.

7. The combination, with a cutter and a reciprocating table, of a gripping-jaw pivoted upon the table and provided with a lever-arm, F', a bar, E, having a limited movement longitudinally with relation to the table, a plate, E', secured to the bar and provided with a lug or 15 projection, e, engaging said lever-arm F', a cushion interposed between the bar E and the plate E', and means applied to the said bar E for actuating the table, substantially as described.

8. The combination, with a cutter and a reciprocating table, of a gripping-jaw mounted upon the table and constructed to act against an opposing surface upon the latter, a sliding bar having limited longitudinal movement 20 relatively to the table, and provided with a part or projection engaging and actuating the jaw, a cushion interposed between said jaw and the projection, a rack formed upon or attached to the said bar, a pinion engaging said 25 rack, and means actuating said pinion for giving a reciprocatory movement to the table, substantially as described.

9. The combination, with a cutter and a reciprocating table provided with a recess, B', near its rear end, of a gripping-jaw pivotally supported upon the table and provided with a lever-arm, F', a sliding bar, E, mounted to slide upon the lower surface of the table and provided with a plate, E', located within the 35 recess B' and provided with a projection or lug, e, engaging the lever-arm F', the said plate E' being made shorter than the recess to allow a limited relative movement of the bar and table, and means applied to the said bar E for 40 actuating said table, substantially as described.

10. The combination, with the table B, provided with the recess B', of the gripping-jaw F, pivotally supported upon the table and provided with a lever-arm, F', and a sliding bar, E, provided with a plate, E', located within the 45 recess B', and provided with a lug or projection, e, said recess B' being provided with cushions b², substantially as described.

11. The combination, with the table B, of the gripping-jaw F, pivoted upon said table and provided with a lever-arm, F', a sliding bar, E, provided with a projection or lug, e, engaging said lever-arm, a spring applied to the said lever-arm for holding the jaw open, 55 and means applied to the said bar for actuating the table, substantially as described.

12. The combination, with a cutter and a reciprocating carriage or table, of a gripping-jaw upon the table, a sliding bar, E, having a limited movement longitudinally with relation 60 to said table, and provided with a projection

or lug actuating said gripping-jaw, a double rack-bar secured to said bar E, a pinion adapted for engagement with both sides of said rack-bar, an oscillating frame affording bearings for the pinion, stops limiting the lateral movement of the frame, curved guides at the ends of the rack-bar adapted for engagement with a projection upon the pinion, a driving-shaft mounted in the frame concentrically with the axis of oscillation of the said frame, and gearing connecting said driving-shaft with the pinion, substantially as described. 70

13. The combination, with the table B and sliding bar E, of the double rack-bar G, attached to said bar E and provided with end rollers, g, a pinion, H, attached to a shaft, H', and adapted for engagement with the said rack-bar, said pinion being provided with a gap, h', adapted to engage the rollers g, a roller, h, 75 upon said shaft H', curved guides J J at the ends of the rack-bar, an oscillating frame, I, affording bearings for said shaft H', a driving-shaft affording pivotal support for the said frame I, gear-wheels upon the driving-shaft 80 and the shaft H', and stops I', for limiting the lateral movement of the said frame I, substantially as described.

14. The combination, with the table B and a gripping device thereon, of a stop, f⁴, movably secured at the rear of the clamping-surfaces of said gripping device, substantially as described. 95

15. The combination, with the table B and the pivoted jaw F, of a stop, f⁴, a lever, F⁴, 100 sustaining said stop, said lever being pivoted upon the table B and provided with a slot and clamping-screw, substantially as described.

16. The combination, with a reciprocating table, of a cutter, a pivotally-sustained support for said cutter, and an arm attached to the said cutter-support and provided with a flexible end piece or part engaging the surface of the table, whereby the cutter is lifted clear of the work in the return or backward movement of the table, substantially as described. 105

17. The combination, with the reciprocating carriage or table, of rotary driving devices connected with the carriage or table for actuating the latter, and provided with an automatic clutch mechanism, and a friction device applied to one of said rotating parts for arresting the movements of the latter when the clutch is disengaged, substantially as described. 115

18. The combination, with the reciprocating table provided with a projection or stop, B², of means for actuating the table, comprising a driving-shaft, K, a driving-pulley mounted 120 upon the shaft and connected with the latter by a clutch, means connected with the clutch for actuating the latter, embracing a lever, N, having a horizontal arm, n', a spring applied to hold the clutch normally disengaged, and a 125 spring-detent, P, applied to engage the said arm n' for holding the clutch in engagement, 130

said stop B² upon the table being adapted for engagement with the said detent, substantially as described.

19. The combination, with a reciprocating carriage or table, of a part or bar constructed to reciprocate with the table and movable to a limited extent with relation to the latter, a gripping device upon the table, a lug or projection upon the said movable part or bar constructed to engage and actuate the gripping device, rotary driving connections acting upon said part or bar for actuating the table and embracing an automatic clutch mechanism, and a friction device applied to one of said 15 rotating parts for arresting the movement of the latter when the clutch is disengaged, substantially as described.

20. The combination, with the reciprocating table provided with a projection or stop, B², 20 of means for actuating the table, comprising a driving-shaft, K, a driving-pulley mounted

upon the shaft and connected with the latter by a clutch, means connected with the clutch for actuating the latter, embracing a lever, N, having a horizontal arm, n', a spring applied 25 to hold the clutch normally disengaged, a spring-detent, P, applied to engage the said arm n', for holding the clutch in engagement and adapted for engagement with the said stop B², the said driving-shaft being provided 30 with washers k' k³, of rawhide or other similar material, located between collars upon the shaft and the bearings of the latter, and means for adjusting the pressure of said washers upon the bearings, substantially as described. 35

In testimony that I claim the foregoing as my invention I affix my signature in presence of two witnesses.

SAMUEL K. WHITE.
